UNITED STATES PATENT OFFICE.

GEORGE B. CANNON, JR., OF BROOKLYN, AND FRANK W. HOWARD, OF NEW YORK, N. Y.

METHOD OF MAKING UMBRELLA-FRAMES.

1,210,900.

Specification of Letters Patent. Patented Jan. 2, 1917.

Application filed May 24, 1915. Serial No. 30,060.

To all whom it may concern:

Be it known that we, GEORGE B. CANNON, Jr., and FRANK W. HOWARD, both citizens of the United States, said GEORGE B. CANNON, Jr., residing at Brooklyn, in the county of Kings and State of New York, and whose post-office address is 154 Rogers avenue, Brooklyn, New York, said FRANK W. HOWARD residing at New York city, in the county of New York and State of New York, and whose post-office address is 9 Fort Washington avenue, New York city, New York, have invented new and useful Improvements in Methods of Making Umbrella-Frames, of which the following is a specification.

This invention relates to umbrellas and particularly to the construction of umbrella frames.

20 A principal object of the invention is to produce a very simple and economical method for constructing part of an umbrella frame, particularly the part comprising the stick, crown and ribs of the umbrella.

25 One of the objects of the invention is to provide a method for constructing and attaching these parts which will avoid the necessity for providing relatively costly connections such as pivotal connections for connecting the ribs with the crown; and also to simplify the construction and the attaching together of the stick, crown-sleeve and ribs.

30 Further objects of the invention will appear more clearly hereinafter.

35 The invention consists in the general procedure and details thereof hereinafter described, all of which contribute to produce an efficient method for making part of an umbrella frame.

40 A preferred embodiment of our invention will be particularly described in the following specification while the broad scope of our invention will be pointed out in the appended claims.

45 In the drawing, Figure 1 is a plan indicating one way of carrying out our invention. Fig. 2 is a cross section taken about on the line 2-2 of Fig. 1. Fig. 3 is a side elevation showing the upper portion of one of the rib members. Fig. 4 is a cross section taken on the line 4-4 of Fig. 6, showing the relation of the crown-sleeve, ribs and stick. Fig. 5 is a vertical section taken through the crown-sleeve and ribs after being united and representing the same without showing the stick. Fig. 6 is a side eleva-

tion partly broken away, showing the stick, crown-sleeve and ribs. Fig. 7 illustrates a step in the method of producing an umbrella frame and is a vertical section through a roll press. Fig. 8 illustrates another manner of securing the ribs and sleeve together and is a vertical section through a mold representing the manner in which this method may be utilized to secure the ribs and sleeve together. Fig. 9 is a side elevation partly broken away, showing the sleeve, ribs and stick attached together when the parts are united in the manner illustrated in Fig. 8.

70 Before proceeding to a detailed description of the parts, it should be said that according to our method, we prefer to unite the ribs and the sleeve integrally preferably through the application of heat. According to this method, in one way we may simply weld the ribs to the sleeve member or we may mold the ribs in the wall of the sleeve. We shall first describe the welding method which we call the "spot-welding" method for securing the ribs to the sleeve member. In order to do this, we prefer to produce an elongated strip 20 of thin sheet metal, and we bend one of the longitudinal edges of this strip so as to form a laterally projecting curved lip 21. We also produce a plurality of rib members 22 with flat extensions or ends 23. These ribs or rib members 22 are preferably formed of resilient material such as steel. The ends 23 are flexible and intended to flex to permit the umbrella to be opened and closed. We arrange these ribs so that they are spaced apart, preferably equidistant along the strip 20 and we hold these ribs with their flat ends lying flat against the strip. By referring to Figs. 2 and 3, it will be seen that the flattened ends 23 are formed with a slight bend or bow 25 just below the lip 21. The extreme ends 26 of the ends 23 may be alined with the longitudinal edge of the strip opposite to the lip 21. With the ribs held upon the strip, we prefer to secure all the ribs to the strip by means of spot-welding applied at about the point 27, Fig. 2, that is, at and near the extreme ends of the ribs. This secures the ribs integrally to the strip. We then cut the strip 20 into short sleeve members or bands 29, by severing the strip at equidistant points as indicated by the dotted lines 28. One of these lengths 29 of the strip may then be treated in either of two ways in order to complete

the formation of the crown-sleeve and secure it to the stick. According to one way, we may simply roll the band or plate 29 into sleeve form with the ends of the plate or band abutting against each other, or, if desired, these ends may be united by a butt weld. In this way a complete sleeve with attached ribs is formed such as that illustrated in Fig. 5, in which the upper ends of the ribs 10 are integrally united to the completed sleeve 30. Furthermore, the ends 23 of the ribs are on the inner face of the sleeve. The lip 21 on the band or strip 20 now forms an outwardly projecting circumferential lip 31 around the lower end of the sleeve. This 15 sleeve may then be secured to an umbrella stick by jamming the stick through the sleeve. The diameter of the stick should be relatively large so that it will fit tightly in the sleeve. When a stick is forced into the sleeve in this way, the flat ends 23 of the rib crush into the face of the stick and this tends to prevent the sleeve from twisting on the stick and also insures a very secure hold 20 of the sleeve on the stick.

Instead of forming the sleeve first and then attaching it to the stick, we may form the sleeve and simultaneously attach it to the stick, simply by rolling one of the sleeve members or bands 29 around the stick. This should be done with considerable force, and may be accomplished in a roll press of 30 any construction, such as that shown in Fig. 7. This press may comprise a block or base 32 carrying a plurality of rollers 33 arranged along a curved line and adapted to coöperate with presser rollers 34 which may be carried on a movable part or frame 35. This frame 35 may be raised and lowered by 35 means of a handle 36 upon which pressure may be exerted. Fig. 7 illustrates the strip as partly rolled around the stick. In starting the strip, the inner end of the strip is laid under the stick 37 and considerable force 40 is then exerted on the handle 36 so as to press the stick down onto the rolls 33 and cause the tongues or ends 23 to crush into the face of the stick. The stick 37 is then rotated forcibly on its axis and this has the 45 effect of bending and wrapping the band or sleeve member around the stick with the flat ends of the ribs substantially embedded in the stick. When this method is practised in the manner illustrated in Fig. 1, it is unnecessary to attach the ends of the band together as the ends of the ribs tend to hold the sleeve against rotation and also prevent the sleeve from sliding longitudinally.

If desired, we may unite the ribs to the 50 sleeve integrally by molding the sleeve around the ribs. In order to accomplish this, we prefer to arrange a plurality of the ribs with the flattened ends of the ribs spaced apart and equidistant from each other in a 55 circumferential arrangement, the axes of

the flattened ends of the ribs being parallel with a common axis. This is preferably accomplished by means of a mold 38 formed into a base or center section 39 and a body section 40. In addition to this, there is provided a ring section 41 which may be formed in two halves, if desired. The flattened and flexible ends 42 of the ribs are arranged equidistant around in the mold, and when they are in place as indicated, the metal in 75 a fluid state is poured into the mold so as to cast the same into a sleeve member 43. The ring section 41 of the mold is employed to form an outwardly curved lip 44 in the finished sleeve. In order to insure that the 80 ribs will have a good hold in the sleeve, we prefer to turn the tips of the ends 42 outwardly as at 45. This practically gives the sleeve a lip at both ends, and in order to enable the sleeve to be withdrawn from the 85 mold, it is necessary to form the mold with a split or sectional center ring 46.

If the ribs, sleeve and stick are produced in the manner indicated in Fig. 7, they will present the appearance indicated in Fig. 6. 90 If they are produced as indicated in Fig. 8, they will present the appearance indicated in Fig. 9. The cover can be secured to the stick and ribs in any suitable manner, and the complete frame should, of course, 95 include a runner of any suitable construction connected by stretchers with the ribs.

It is understood that the embodiment of the invention set forth herein is only one of the many embodiments or forms the invention may take, and we do not wish to be limited in the practice of the invention nor in our claims to the particular embodiment set forth.

What we claim is:

1. The method of making part of an umbrella frame which consists in forming a plurality of resilient rib members with flexible substantially flat ends, arranging said flexible ends spaced apart and adjacent to each other, and integrally uniting said flat ends to a sleeve member.

2. The method of making part of an umbrella frame which consists in forming a plurality of resilient rib members with substantially flat flexible ends, arranging said flexible ends spaced apart and adjacent to each other, integrally uniting said flat ends to a sleeve member, and securing the sleeve member upon an umbrella stick.

3. The method of making part of an umbrella frame which consists in forming a plurality of rib members with flexible substantially flat ends, holding said rib members with said flat flexible ends spaced apart upon a substantially flat strip, securing the said flat extensions to said strip, and then rolling said strip into a sleeve.

4. The method of making part of an umbrella frame which consists in forming a 130

plurality of rib members with flexible substantially flat ends, holding said rib members with said flat flexible ends spaced apart upon a substantially flat strip, welding the 5 said flat extensions to said strip, and then rolling said strip into a sleeve.

5. The method of making part of an umbrella frame which consists in forming a plurality of rib members with flexible substantially flat ends, holding said rib members with said flat flexible ends spaced apart 10 upon a substantially flat strip, securing the said flat extensions to said strip, and then rolling said strip into a sleeve around the 15 periphery of an umbrella stick.

6. The method of making part of an umbrella frame which consists in forming a

plurality of rib members with flexible substantially flat ends, holding said rib members with said flat flexible ends spaced apart 20 upon a substantially flat strip, securing the said flat extensions to said strip, and then rolling said strip into a sleeve around the periphery of an umbrella stick with said flat ends disposed inwardly and crushed into 25 the face of the stick.

In testimony whereof we have hereunto set our hands in presence of two subscribing witnesses.

GEORGE B. CANNON, JR.
FRANK W. HOWARD.
